UNITED STATES PATENT OFFICE.

NORMAN WILLIAM McLACHLAN, OF LONDON, ENGLAND, ASSIGNOR TO WIRELESS MUSIC LIMITED, OF LONDON, ENGLAND.

LOUD-SPEAKER.

Application filed January 16, 1928, Serial No. 247,226, and in Great Britain January 11, 1927.

The present invention relates to loud speakers of the type in which a diaphragm or other surface of relatively large size is in operative connection with a driving element which is 5 adapted to be set in vibration electrically.

Many attempts have been made to produce a loud speaker of this type, which shall reproduce sounds which appear to the ear to be at substantially uniform intensity over a 10 wide band of frequencies. It has been found that by properly adjusting the nature and dimensions of the various components, appreciable improvements in the performance of a loud speaker can be effected.

15 It is a difficult matter to design a diaphragm or other sound producing surface which shall be sufficiently light and stiff to vibrate as a whole over the band of frequencies of importance in sound reproduction, for 20 example from 80 to 6000 cycles per second. It is also difficult to design a driving element which shall give an even response over this band of frequencies without excessive damping which renders the system insensitive.

25 The present invention takes advantage of the fact that certain sound producing surfaces "break up" progressively as the frequency applied to them is increased, that is to say, the effective area in vibration decreases progressively with increasing frequency. By 30 using a driving element having a natural frequency higher than has been customary in the past, and by coupling to it a sound producing surface which is of such size and 35 of such material and shape that it only commences to vibrate as a whole in the neighbourhood of the lowest frequency to be reproduced, a very uniform overall response characteristic can be obtained and at the same time 40 pronounced resonances are eliminated.

According to the present invention the natural frequency of the driving element of a loud speaker of the type set forth when detached from the sound producing surface 45 is made greater than 2500 cycles per second.

All parts which can be regarded as vibrating effectively with the driving element are considered to form part thereof. Thus where a cantilever reed is utilized as driving 50 member and is connected to a conical diaphragm by means of a metal rod and metal nuts, the connecting means are regarded as forming part of the driving means.

The sound producing surface is made of 55 such size and shape and of such material

that it does not freely vibrate as a whole above 150 cycles per second. The question as to whether the surface is vibrating as a whole or not may be tested by dusting a fine powder on to the surface. If any nodes are present 60 these will then be rendered visible by a piling up of the powder upon them. The presence of nodes indicates that the surface is not vibrating as a whole.

The natural frequency of the vibratory 65 parts of the loud speaker, which comprise the driving element, the connecting means and the diaphragm, as calculated from the stiffness of the driving element and the mass of the vibratory parts, regarded as lump 70 loaded upon the driving element, lies preferably between 700 and 1100 cycles per second.

The diaphragm is preferably conical and supported at its periphery with only sufficient restraint to provide the desired terminal 75 impedance.

Suitable means are preferably provided for minimizing the interaction of pressure waves generated by the front and rear surfaces of the diaphragm respectively, in order 80 to preserve the lower tones. Such means may comprise a box, the front end of which is sealed by the diaphragm and its flexible annular member, whilst apertures of suitable size may be formed in the rear of the box to 85 reduce undesirable box resonance, and possible reduction of the lower tones by interference.

The invention is illustrated in the accompanying drawings, in which—

90 Fig. 1 shows diagrammatically a method of construction of a diaphragm;

Fig. 2 a schematic sectional elevation of a loud speaker in accordance with the invention;

95 Figure 3 is a side view of a movement arranged to be mounted in the loud speaker casing showing a portion thereof taken along the line 3—3 of Figure 4, and

Figure 4 is a plan view of the movement. 100

Referring to the drawings, the diaphragm 1, which in its final form is conical, is made of hot press paper about 0.2 millimetres in thickness and weighing about 0.015 grammes per square centimetre. A circle A, 8 $\frac{5}{8}$ inches 105 radius, is first cut from the paper and two radii B and C, 60° apart are drawn thereupon. One cut is then made along one of these radii (say B) and another cut D along a line parallel to and about $\frac{1}{2}$ inch from the other 110

radius (C) between the two radii and extending from the former radius (B) to the periphery of the circle. The $\frac{1}{2}$ inch wide strip so formed between the radii serves as 5 overlap in joining the sides of the segment to form a cone which may be effected with suitable glue. A number of radial incisions are made around the edge of the cone extending inwards about $\frac{1}{2}$ inch, and the tongues so 10 formed are bent outwards to lie in the plane of the cone base. These tongues are then glued on to a sheet of thin paper and when dry the circular portion of this paper inside the tongues is removed. Alternatively, in- 15 stead of making the radial incisions the outer rim may be pressed into shape by means of a male and female jig, the outer edge of paper being previously moistened. There is now, therefore, a cone of about $13\frac{3}{4}$ inches base 20 diameter, having therefore a projected area slightly less than 1000 sq. cms. and with an apex angle of about 113° , bounded by a flat annular member of thin paper, such as that commonly employed for charcoal sketches. 25 The diaphragm so formed is warmed to remove moisture and then treated all over both sides with a suitable waterproofing varnish, such as a solution of cellulose. After this treatment the diaphragm is preferably 30 left for a week in a dry warm atmosphere. The diaphragm is then glued to the edge of a wooden frame 2, $16\frac{1}{4}$ and $17\frac{1}{4}$ inches wide, internally and externally respectively, and about 2 inches deep, with the conical portion 35 projecting through the frame. If desired, the edge of the thin paper of the diaphragm which is to be glued may be left unvarnished to facilitate gluing, and when dry, varnish may be applied in the neighbourhood of the 40 join.

The loud speaker casing consists of a stiff wooden box 3, for example of $\frac{3}{8}$ inch thick wood, whose dimensions are $17\frac{1}{4}$ inches square internally and $7\frac{1}{4}$ inches deep. The back of 45 the box is provided with apertures 4 having a total area of about 60 square inches. The frame carrying the diaphragm is inserted within the front of the box and is held firmly 50 against fillets secured around the inside of the box by suitable blocks secured to the inside of the casing in front of the frame. The diaphragm and frame may therefore be readily 55 replaced if necessary. The front of the diaphragm in its final position is preferably about $\frac{1}{4}$ inch behind the front edge of the box and the front of the box may be covered with thin silk (not shown) secured in position by means of a beading.

In order to strengthen the cone in the neighbourhood of its apex a small cone 5 of the same material as the larger cone is preferably 60 glued over the larger cone. This may be made from a circular piece of the paper 1 inch in diameter, slit along a radius and over- 65 lapped to fit snugly over the large cone. The

overlapped portion of the smaller cone should be arranged at the opposite side to the overlap of the large cone.

The annulus 1' of light paper around the conical portion of the diaphragm, which annulus is of minor or negligible import as a sound radiating surface, serves to support the diaphragm to prevent the passage of pressure waves around the periphery of the cone, to preserve the lower tones, and to impose a 75 terminal impedance upon the diaphragm such as will substantially prevent reflection and consequent resonance. Instead of paper, other materials which fulfil these conditions may be used.

The diaphragm hereinbefore described is adapted to be impelled by a reed loud speaker movement 6, through a threaded rod 7, which is attached thereto by screwed conical cups 8 and 9, as shown in Fig. 2. The movement is 85 mounted in the rear of the box 3 and is preferably acoustically insulated therefrom by means of a rubber ring or the like 10.

As stated above, any suitable type of movement complying with the requirements 90 of the present invention may be employed, but in order that the relative dimensions of the apparatus as a whole may be appreciated, one suitable movement as shown in Figures 3 and 4 will now be described in detail.

The said movement comprises a base piece 12 of flat brass which is adapted to be attached to the back of the box 4. A relatively large boss 13, having a central hole 14, is provided on the rear side of the base. A U-shaped magnet 15 is secured at its base to a plate 16 and a spindle 17 secured to the plate projects therefrom away from the magnet. This spindle is made a good sliding fit in the hole 14 through the boss and a featherway 18 is provided in the spindle and is engaged by a small block 19 which is pressed into position by means of a screw 20 passing from the outside to the inside of the boss and preventing rotation of the spindle relatively to the boss 100 but permitting free sliding thereof. The end of the spindle remote from the plate is threaded to receive an adjusting knob 11, whilst a helical spring 21 surrounds a small locating spigot 22, formed upon the base piece upon 105 the opposite side to the boss 13 and co-axial therewith, and tends to force the plate 16 carrying the magnet in a direction away from the base. The knob is provided with a groove 110 which is engaged by a plate secured to the rear face of the boss, and this permits rotation of the knob but prevents translation thereof although this arrangement is not shown in the drawings. The magnet is provided with two inwardly projecting pole 115 pieces 23 of suitable silicon alloy, having an air gap between them, and these pole pieces are united for rigidity, by means of side plates 24 of non-magnetic material. The pole pieces are tapered at their tips, towards their up- 120

per surfaces, in order to concentrate the flux in the air gap. A coil 25, adapted to carry audio frequency currents, is arranged around each pole piece, and these coils may be connected in series. The resistance of the coils in series may be 2000 ohms. A pillar 26 is secured to and projects from the base on the opposite side to the boss, and parallel with the spindle and upon its ends, projecting at right angles to the pillar, is secured a reed 27 of mild steel or suitable silicon steel alloy which passes just above the gap between the pole pieces. It will be readily understood that the adjusting knob permits of the movement of the magnet pole pieces relatively to the reed. The thin mild steel rod 7 is riveted into the reed at a point over the middle of the air gap and projects at right angles to the reed. The mild steel rod 7 is provided with a thread upon which is screwed a conical cup 9 into which the apex of the cone diaphragm 1 seats when the movement is placed in position upon the box (see Fig. 2). Alternatively, the conical cup may be formed integral with the rod or may be soldered thereto. The end of the threaded rod projects through to the front of the cone and a conical nut or cup 8 is screwed on to secure the centre of the diaphragm firmly to the rod. The angles of the conical cup and of the conical nut should be approximately equal to that of the cone diaphragm.

The free length of the reel is 2 centimetres, the distance from the support to the threaded rod 1.25 centimetres, the width of the reed 0.64 centimetres and the thickness of the reed 0.18 centimetres. The mass of the connecting means (threaded rod, cup and nut) is 2.5 grammes and the mass of the conical portion of the diaphragm is 23 grammes. The stiffness of the reed, which may be of turbotalloy or steel, is found by calculation from its dimensions to be 9×10^8 dynes per centimetre, and its natural frequency about 3500-4000 cycles per second.

Where a simple cantilever reed of constant rectangular cross section is used its natural frequency may be determined by Rayleigh's approximate formula:

$$f = \frac{84590 t}{l^2}$$

where f is the natural frequency, t the thickness in centimetres and l the length in centimetres.

With the connecting means the natural frequency is approximately 2800 cycles per second.

If the mass of the conical portion of the diaphragm, together with that of the connecting means, be assumed to be lump-loaded on the reed at the point of attachment of the connecting means thereto, the calculated natural frequency of the vibratory system will be found to be about 1000 cycles per sec-

ond. An allowance for the mass of the reed lowers the calculated frequency to 950 cycles per second. The natural frequency of the diaphragm considered as a mass vibrating upon its paper annular member, is below good audibility—about 25 cycles per second.

Although the values given above have been found to give the best results, certain small departures from these are permissible. It will be noted that certain of the figures given for the natural frequency of the vibratory system are obtained by calculation, taking only stiffness and mass into consideration. In practice, other considerations may enter into the determination of the value of the frequency.

I claim:

1. A sound reproducing device comprising a sound producing member of relatively large size and a vibrating driving element in operative connection with said member, the natural frequency of said driving element being between 2500 cycles and 3000 cycles per second, said sound producing member being of such nature and dimensions that it does not freely vibrate as a whole above 150 cycles per second.

2. A sound reproducing device comprising a sound producing member of relatively large size, a vibrating reed operatively connected with said member, the natural frequency of said reed being greater than 2500 cycles per second, said sound producing member being of such size, shape and material that it does not freely vibrate as a whole above 150 cycles per second.

3. A sound reproducing device comprising a sound producing member of relatively large size, a vibrating driving element, means operatively connecting said producing member with said driving element whereby said element is so dimensioned that its natural frequency when loaded at its point of attachment with said member, with a mass equal to the mass of said member and the mass of said connecting means, is between 700 and 1100 cycles per second, said sound producing member being of such nature and dimensions that it does not freely vibrate as a whole above 150 cycles per second.

4. A sound reproducing device comprising a conical sound producing member of relatively large size, and a vibrating driving element operatively connected with said member, the natural frequency of said driving element being between 2500 cycles and 3000 cycles per second, said sound producing member being of such nature and dimensions that it does not freely vibrate as a whole above 150 cycles per second.

5. A sound reproducing device comprising a conical sound producing member of relatively large size, a vibrating driving element operatively connected with said member, the natural frequency of said driving element be-

- ing between 2500 and 3000 cycles per second, said sound producing member being of such nature and dimensions that it does not freely vibrate as a whole above 150 cycles per second,
- 5 a rigid body surrounding said conical sound producing member, and a substantially flat annular member of thin material secured to said rigid body and the outer marginal edge of said sound producing members.
- 10 6. A sound reproducing device comprising a sound producing member of relatively large size, a support therefor, a driving element,
- which is adapted to be set in vibration, and means for connecting said driving element with said sound producing member, wherein 15 the natural frequency of said driving element is greater than 2500 cycles per second and wherein the natural frequency of said sound producing member, when detached from said connecting means, is less than 30 cycles per 20 second.

In testimony whereof I have signed my name to this specification.

NORMAN WILLIAM McLACHLAN.
